E. K. BOTTLE,

MANIFOLDING SALES BOOK.

APPLICATION FILED NOV 24 1811

1,108,486.

Patented Aug. 25, 1914

UNITED STATES PATENT OFFICE.

EDWARD KIRBY BOTTLE, OF ELMIRA, NEW YORK, ASSIGNOR TO AMERICAN SALES BOOK COMPANY, LIMITED, OF TORONTO, CANADA, A CORPORATION OF CANADA.

MANIFOLDING SALES-BOOK.

1,108,486.

Specification of Letters Patent. Patented Aug. 25, 1914.

Application filed November 24, 1911. Serial No. 662,210.

To all whom it may concern:

Be it known that I, EDWARD KIRBY BOTTLE, a citizen of the United States, residing at Elmira, in the county of Chemung and State of New York, have invented certain new and useful Improvements in Manifolding Sales-Books, of which the following is a full, clear, and exact description, such as will enable others skilled in the art to which it appertains to make and use the same.

This invention relates to salesbooks, and with regard to certain more specific features thereof, to manifolding triplicate salesbooks.

One of the objects of this invention is to provide a salesbook which will be durable in construction and adapted for rapid and convenient manipulation.

Another object is to provide a simple, compact and practical salesbook which will permit of ready formation of records in triplicate.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawing, wherein is shown one of various possible embodiments of this invention, Figure 1 is a perspective view showing the book in operative position; Fig. 2 is a central longitudinal sectional view; Fig. 3 is a central transverse sectional view; and Fig. 4 is a detail sectional view, showing one of the features of the invention.

Similar reference characters refer to similar parts throughout the different views of the drawing.

Referring now to the drawing in detail, and more particularly to Fig. 1, there is shown at 1 a rear binding cover or support connected by means of a flexible hinge 2, extending along one of the side edges, with an upper cover 3, adapted to be folded over the book to protect the leaves thereof when not in use. At the opposite side edge is a second flexible hinge 4, connecting the cover 1 with a side edge of a back 5. This back 5 is provided with an upwardly projecting tip up flange 6, extending along the hinge side edge thereof, which also forms an abutment preventing lateral movement of a pad

7 mounted upon the back 5. This flange 6, as clearly shown in Figs. 1 and 3, is preferably made of a strip of metal folded over upon itself and inclosing at the lower part thereof a wire bail or pad-holding member 8 adapted to be inserted between the cardboard backing of the pad, indicated at 9, and the lower leaves thereof as the pad is placed upon the back 5. This construction permits the ready removal of the pad by raising the bound edge which causes the bail 8 to swing about its point of connection with the flange 6, after which the pad may be moved laterally until the backing 9 slips out of engagement with the bail.

The pad 7 is preferably made from a continuously folded or zig-zag web forming a plurality of sets of original and duplicate leaves 10 and 11, respectively, bound together along their side edge by means of staples 12. These leaves may be conveniently separated from the binding edge along perforated lines 13. At the ends of each leaf are other weakening lines 14 whereby the leaves may be separated from each other. Bound together with the leaves of this pad is also a double-faced carbon sheet 15 which is wider at its bound edge than its opposite free edge, due to the cutaway portions at both ends or transverse edges. By cutting the carbon sheet, as shown at 16 and 17, the tendency to tear the leaf along its bound edge, as the leaves of the pad are torn along the line 13, is practically eliminated, for as the leaf 11, for instance, is raised, it will cause the carbon sheet to move laterally out of the way. This carbon sheet also extends slightly beyond the edge of the pad opposite its binding edge, as shown at 18, so as to completely cover the duplicate leaves at all times. By forming the sheet 15 as herein shown the efficiency of the book is in no way decreased as the top of the leaves of the pad is usually devoted to the name and address of the user, which obviously does not require a reproduction upon the other leaves of the book.

Along the side edge of the cover 1, adjacent the flexible hinge 2, is an upwardly projecting flange 19 which acts as an abutment for the bound edge of a triplicate pad 20. This pad is removably secured to the back 1 by means of a pad-holder or bail 21 adapted to be interposed between the bottom leaf of the pad and the back 22 in a

manner similar to the holding means of the pad 7. The leaves of this pad are adapted to register with the leaves of the pad 7, one of which, as shown at 23, is adapted to be interposed between the original leaf 10 and the upper surface of the carbon sheet 15, whereby as the record is recorded upon the leaf 10, it will be transferred to the reverse side of the leaf 23 by means of one face of the carbon sheet 15, and also upon the duplicate leaf 11 because of the opposite face of the carbon sheet. In this manner a triplicate record of any transaction is conveniently and quickly made.

15 After completing the recording of the transaction, it being assumed that the operator is holding the book in his left hand, he presses downwardly with his thumb upon the flange 6, which causes the back 5 and pad 7, mounted thereon, to swing upwardly into the position shown by the dotted lines in Fig. 3. This upwardly swinging movement of the original pad causes the leaf 23 to be drawn out of its registering position 20 and fall by gravity onto the upper surface of the back 1, as indicated by the position of the leaves 24. Then as the operator releases the pressure upon the flange 6, the parts will return to normal position under the action of a flat spring 25, shown in detail in Fig. 4, thus filing away one complete record of the transaction.

The manner of operating a book of this character is substantially as follows: Assuming the pads to be inserted in the holder in the position shown, the bottom leaf of the triplicate pad is inserted beneath the top or original leaf of the pad 7. With the carbon sheet beneath the triplicate leaf, 30 the record is then made upon the original leaf, producing a triplicate record in the manner above set forth. After completing the transaction the pad 7 is swung about the hinged connection 4, which withdraws the triplicate leaf from between the top set of leaves of the pad and permits it to fall into the filing space between the cover 1 and back 5. The original leaf is then grasped by the right hand of the operator when the book is held in the left hand in the position shown in Fig. 4 and moved upwardly and forwardly to tear the duplicate leaf from the pad along the dotted lines 13. This movement forces the carbon sheet outwardly 45 to the left without tearing the same. The set of leaves upon which the transaction has just been made is then moved rearwardly, which tears the next original leaf from the pad; the carbon sheet is swung back over the next duplicate leaf, and the second triplicate leaf placed thereupon, after which the second original leaf is laid thereover, and the 3rd set of original and duplicate leaves is torn along the line 14 at the bot-

tom. The book is then ready for the second operation.

It will thus be seen that this invention provides a simple and practical form of triplicate salesbook, accomplishing, among others, all of the objects and advantages 70 above set forth.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense.

Having described my invention, what I claim as new and desire to secure by Letters Patent is:

1. In a device of the character described, in combination, a cover, a pad removably secured to one side of said cover, a back hinged to the opposite side of said cover, a pad removably mounted on said back, the leaves of said pads being adapted to register when in operative position, and tip-up means adapted to move said second mentioned pad out of operative relation with the first mentioned pad.

2. In a device of the character described, in combination, a cover, a pad removably secured to one side of said cover, a back hinged to the opposite side of said cover, a second pad removably mounted on said back, the leaves of said pads being adapted to register when in operative position, tip-up means for moving one of said pads about one of its edges as an axis, and means for returning the last mentioned pad to operative position.

3. In a device of the character described, in combination, a cover, a pad removably secured to one side of said cover, a back hinged to the opposite side of said cover, a second pad removably mounted on said back, the leaves of said pads being adapted to register when in operative position, tip-up means for moving one of said pads about one of its side edges as an axis, and resilient means connecting the back with said cover for returning the last mentioned pad to operative position when released.

4. In a manifolding sales book, in combination, a support, a member hinged to said support, pads carried by said support and member and means for holding said support and member in normal position.

5. In a manifolding sales book, in combination, a support, a member hinged to said support, pads mounted on said support and member respectively, the leaves of said pads being adapted to register when in operative position, and means for holding said support and member in normal position.

6. In a manifolding salesbook, in combination, a support, a member hinged to said support, pads mounted on said support and member respectively, and resilient means associated with the hinge-connection for returning the parts to normal position.

7. In a device of the character described, in combination, a support, a member hinged to said support, a spring associated with said hinge for maintaining the parts in normal position, a pad removably mounted on said support, a second pad coacting with said first-mentioned pad and removably mounted on said member, and a double-face carbon sheet associated with one of said pads whereby a record is produced in triplicate.

8. In a device of the character described, in combination, a support, a member hinged to said support, a pad of triplicate leaves secured to one of said parts, a pad comprising a plurality of sets of original and duplicate leaves mounted upon the other, the leaves of said second mentioned pad being bound together along one edge, and a carbon sheet bound with the leaves of one pad having its edge normal to the binding edge curved whereby it will be moved out of the way as the leaves are torn from said pad.

9. In a device of the character described, in combination, a support, securing means along one side of said support, a pad of triplicate leaves held by said securing means, a flexible hinge at the opposite side of said support, a member connected therewith by said hinge, closing means associated with said hinge, a pad mounted on said member, said pad comprising a plurality of sets of original and duplicate leaves, the leaves of both of said pads adapted to register when in operative position, and manifolding means associated with one of said pads.

10. In a device of the character described, in combination, a support, securing means along one side of said support, a pad of triplicate leaves held by said securing means, a flexible hinge at the opposite side of said support, a member connected therewith, a pad mounted on said member, said pad comprising a plurality of sets of original and duplicate leaves, the leaves of both of said pads being adapted to register when in operative position, and manifolding means bound with the leaves of one of said pads having its edge disposed at an angle to the binding curved whereby the sheet will be moved aside as the leaves are torn from the pad.

11. In a device of the character described, in combination, a support, securing means along one side of said support, a pad of triplicate leaves held by said securing means, a flexible hinge at the opposite side of said support, a member connected there-

with, a pad mounted on said member, said pad comprising a plurality of sets of original and duplicate leaves, the leaves of both of said pads adapted to register when in operative position, and a double-face carbon sheet bound with the leaves of one pad wider at its bound edge than at its opposite edge.

5. In a heavier-than-air flying machine in combination, a cover, an abutment along one edge of said cover, a pad removably secured thereto and held against lateral movement by said abutment, a back, a flexible hinge connecting the opposite edge of said cover with said back, an upwardly projecting flange on said back, a removable pad held by said flange against lateral movement, said flange forming a tip-up means for rotating the last mentioned pad and back about its flexible hinge connection with said cover, and manifolding means associated with one of said pads whereby a record may be produced in triplicate.

13. In a device of the character described, in combination, a cover, an abutment along one edge of said cover, a pad removably secured thereto and held against lateral movement by said abutment, a back, a flexible hinge connecting the opposite edge of said cover with said back, an upwardly projecting flange, a removable pad held by said flange against lateral movement, said flange forming a tip-up means for moving the last mentioned pad and back about the flexible hinge connection with said cover, spring means for holding said parts in normal position, and manifolding means associated with one of said pads whereby a record may be produced in triplicate.

14. In a device of the character described, in combination, a cover, an abutment along one edge of said cover, a pad removably secured thereto and held against lateral movement by said abutment, a back, a hinge connecting the opposite edge of said cover with said back, a removable pad held by said flange against lateral movement, said flange forming a tip-up means for moving the last mentioned pad and back about its hinge connection with said cover, spring means for holding said parts in normal position, and manifolding means associated with one of said pads whereby a record may be produced in triplicate, said manifolding means comprising a double-face carbon sheet so shaped as to be moved to one side as the leaves are torn from the pad to which the sheet is connected.

15. In a device of the character described, in combination, a cover, a triplicate pad removably secured to a side edge of said cover, a back flexibly hinged to the opposite side of said cover, a pad of original and duplicate leaves mounted upon said back

adapted to register with the leaves of the triplicate pad when in operative relation thereto, and means adapted to be engaged by the thumb of the operator for swinging said back about its hinged connection for permitting the leaves to be filed between said cover and said back.

16. In a device of the character described, in combination, a cover, a triplicate pad 10 movably secured to a side edge of said cover, a back flexibly hinged to the opposite side of said cover, a pad of original and duplicate leaves mounted upon said back adapted to register with the leaves of the 15 triplicate pad when in operative relation thereto, tip-up means for swinging said back about its hinged connection to permit the triplicate leaves to be filed between said cover and said back, and spring means connected with said device for restoring the 20 back to normal position.

17. In a device of the character described, in combination, a cover, a triplicate pad hinged to one of the side edges of said cover, a duplicate and original pad connected with 25 the opposite side edge of said cover, the leaves of said pads adapted to register when in operative position, and a carbon sheet bound with the leaves of said second mentioned pad along one edge thereof and extending across and beyond the opposite side edge of the upper sheets whereby as the 30 pad becomes reduced in thickness said carbon sheet will completely cover the lower-most sheets.

35 In testimony whereof I affix my signature, in the presence of two witnesses.

EDWARD KIRBY BOTTLE.

Witnesses:

A. L. GENTHNER,
N. K. GILBERT.

It is hereby certified that in Letters Patent No. 1,108,486, granted August 25, 1914, upon the application of Edward Kirby Bottle, of Elmira, New York, for an improvement in "Manifolding Sales-Books," an error appears in the printed specification requiring correction as follows: Page 3, strike out line 73, and insert the numeral and words *12. In a device of the character described;* and that the said Letters Patent should be read with this correction therein that the same may conform to the record of the case in the Patent Office.

Signed and sealed this 29th day of September, A. D., 1914.

[SEAL.]

R. F. WHITEHEAD,
Acting Commissioner of Patents.
